UNITED STATES PATENT OFFICE.

ANDREW I. PAYNE, OF DOLAND, SOUTH DAKOTA.

TOBACCO-PIPE.

1,181,922.

Specification of Letters Patent.

Patented May 2, 1916.

Application filed February 6, 1915. Serial No. 6,663.

To all whom it may concern:

Be it known that I, ANDREW I. PAYNE, a citizen of the United States, residing at Doland, in the county of Spink and State 5 of South Dakota, have invented new and useful Improvements in Tobacco-Pipes, of which the following is a specification.

The invention relates to tobacco pipes, and has for an object to provide a simple 10 pipe which will provide a clean and sanitary smoke and in which the few parts are so arranged that they can be readily disassembled for the purpose of cleaning the interior surfaces or passages of the parts.

15 The invention contemplates, among other features, the provision of a pipe which will prevent moisture from the mouth of the smoker from coming in contact with the tobacco and in which, furthermore, the tobacco will be entirely consumed to leave a clean ash.

A still further embodiment of the invention resides in the provision of a pipe in which the smoke is forced to take certain 20 courses or passages through the pipe to cool the same before it reaches the mouth of the smoker.

In the further disclosure of the invention reference is to be had to the accompanying 25 drawings, constituting a part of this specification, in which similar characters of reference denote corresponding parts in all the views, and in which:

Figure 1 is a vertical sectional view taken 30 through a pipe; Fig. 2 is a horizontal sectional view taken on the line 2—2 in Fig. 1; and Fig. 3 is a perspective view of one of the removable parts.

Referring more particularly to the views, 35 I disclose a pipe body 10 consisting of the usual bowl 11 and stem 12, the stem having a suitable longitudinal passage 13 therein. A tobacco receptacle 14 is provided for disposition in the bowl 11, said receptacle having an outwardly formed annular flange 15 at its upper edge which, contacting with an inwardly projecting edge 16 of the bowl, supports the receptacle 14 so that the main portion thereof will be in spaced relation to 40 the wall of the bowl to provide a chamber 17 entirely surrounding the tobacco receptacle. The tobacco receptacle has its bottom 18 suitably perforated as shown so that the smoke can readily pass into the chamber 17.

An opening 19 is formed in the bottom of

the bowl 11 and a member 20 is adapted for insertion through the opening, said member consisting, more particularly, of a dividing member 21 in the nature of a vessel or receptacle and which, extending into the chamber 17, divides the same into compartments 22 and 22' communicating with each other at their upper ends, the said vessel or receptacle 21 being thus in spaced relation to the receptacle 14 and the pipe body 10 and having its free edge also spaced from the pipe body and tobacco receptacle to afford communication between the compartments 22 and 22'. The vessel or dividing member 21 is supported on suitable standards 23 carried on a closure 24 for the opening 19 and which has threaded engagement with the pipe body to close the opening, said closure also including a wall 25 preferably formed by recessing the closure. The vessel or dividing member 21 has a face 26 of its wall provided with a series of grooves 27 to facilitate the passage of smoke, said grooves therefore constituting smoke passages.

When the tobacco receptacle 14 has been filled with tobacco and the same has been ignited, suction produced at the mouth of the stem 12 will cause the smoke to pass 50 through the apertured bottom 18 into the first or innermost compartment 22' and in which the smoke by the suction produced will be caused to pass upwardly over the upper edge of the member 21 and into the other or outer compartment 22. The smoke will now pass downwardly in the compartment and thence through the stem 12 to the mouth of the smoker. Now it will be apparent that any moisture in the stem or 55 which may enter the bowl 11 of the pipe body will pass into the well 25 formed on the closure 24 and thus the tobacco containing receptacle will be spaced and in superposed relation to the well so that any moisture cannot come in contact with the tobacco or ashes in the receptacle, thus keeping the tobacco in a state and condition which will result in it being entirely consumed when subjected to fire and the suction produced 60

It will be seen that the various parts can be readily removed; that the tobacco receptacle 14 can be easily removed from the pipe bowl and that the member 20 can be independently removed from the pipe bowl so that its various parts and structures can be

easily cleaned in order to keep the pipe in a sanitary and wholesome condition.

Having thus described my invention, I claim:

- 5 1. In a pipe, the combination with a pipe body including a bowl and a tubular stem having a passage therein, of a tobacco receptacle supported in the bowl and having its main portion in spaced relation to the 10 wall of the bowl to form a chamber, said tobacco receptacle having an apertured bottom, a dividing member extending into the chamber to divide the same into intercommunicating compartments, said dividing member 15 encircling the tobacco receptacle and lying in spaced relation to the tobacco receptacle and bowl, a closure for connection with the pipe bowl to close the opening in the bottom thereof, said closure supporting the dividing member in position within 20 the bowl, and a well in the said closure, said well being formed adjacent the inner end of the tubular stem.
2. In a pipe, the combination with a pipe body including a bowl and a tubular stem having a passage therein, of a tobacco receptacle supported in the bowl and having its main portion in spaced relation to the wall 25 of the bowl to form a chamber, said tobacco receptacle having an apertured bottom, a dividing member extending into the chamber to divide the same into intercommunicating compartments, said dividing member encircling the tobacco receptacle and lying in 30 spaced relation to the tobacco receptacle and bowl, a closure threadedly connected with the bottom of the pipe bowl to close the opening in the bottom thereof, said closure 35

supporting the dividing member in position within the bowl, a well in the said closure, 40 said well being formed adjacent the inner end of the tubular stem, and longitudinal smoke passages formed in the wall of the dividing member for facilitating the passage of smoke from one of the compartments 45 in the bowl to the other.

3. In a pipe, the combination with a pipe body including a bowl and a tubular stem having a passage therein, of a tobacco receptacle supported in the bowl and having 50 its main portion in spaced relation to the wall of the bowl to form a chamber, said tobacco receptacle having an apertured bottom, a dividing member extending into the chamber and encircling the tobacco receptacle to divide the chamber into intercommunicating compartments, said dividing member lying in spaced relation to the tobacco receptacle and bowl, a closure threadedly connected with the bottom of the pipe bowl 55 to close the opening in the bottom thereof, standards carried by the closure for supporting the dividing member in position within the bowl, a well in said closure, said well being formed adjacent the inner end 60 of the tubular stem, and longitudinal smoke passages formed in the inner wall of the dividing member for facilitating the passage of smoke from one of the compartments 65 in the bowl to the other.

In testimony whereof I affix my signature in presence of two witnesses.

ANDREW I. PAYNE.
